UNITED STATES PATENT OFFICE

CYRUS P. BACHELDER, OF PAWTUCKET, RHODE ISLAND.

BURGLAR-ALARM.

SPECIFICATION forming part of Letters Patent No. 329,253, dated October 27, 1885.

Application filed May 7, 1884. Serial No. 130,683. (Model.)

To all whom it may concern:

Be it known that I, CYRUS P. BACHELDER, a citizen of the United States, residing in the town of Pawtucket, in Providence county, 5 of the State of Rhode Island, have invented a new and useful Improvement in Burglar-Alarms, of which the following is a specification.

My invention relates to improvements in 10 burglar-alarms adapted to be attached to the inside of the door or located within a room, and so connected with the knob-spindle of the door that upon said spindle being turned a bell is rung, the object being to provide a 15 catch which can be so fixed as to allow the bell to ring whenever the knob-spindle is turned; to provide improved means whereby said knob may be turned without ringing the bell; and, further, to provide means which, when placed 20 in a certain position, will allow the bell to ring continuously, when the knob is turned, until the force of the actuating-power is expended.

With these ends in view the invention consists in the improved construction and combination of parts hereinafter fully described, 25 and pointed out in the claims.

In the drawings, Figure 1 is an elevation of a sufficient portion of a door to illustrate the 30 application of my invention thereto. Fig. 2 is a longitudinal vertical section of the device. Fig. 3 is a transverse vertical section. Fig. 4 is a side elevation, and Fig. 5 is a detail view of the yoke or clamp employed for attaching 35 or connecting the alarm with the knob-spindle. Fig. 6 is a detached perspective view of the casing.

In the accompanying drawings, in which like letters of reference indicate corresponding 40 parts in all the figures, A represents a suitable bracket or casing, at the upper end of which is journaled a gear-wheel, B, the shaft a' of which is squared at its end to receive a key for turning said shaft, for a purpose which will 45 be explained. Connected with the shaft a' is one end of a coil-spring, C, which is wound around said shaft and connected with the bracket or casing at its other end. On the shaft a' is located a sleeve or tube, b, through 50 which extends the squared end of the said shaft. The said tube or sleeve is interiorly

threaded, and fitting upon the same is a bell, c, which is held in place by a nut, d, open at its end, to allow the insertion of a key for winding the spring. On the casing is rigidly 55 mounted upon a shaft, e, a gear-wheel, D, which meshes with the gear-wheel B. In the sides of the casing, just below the gear-wheel D, is mounted a shaft, C', having near its inner end a lantern-wheel, g, which lantern-wheel 60 meshes with the gear-wheel D. It will thus be seen that if said coil-spring is wound up it will impart motion to the gear-wheel B, which will, through the medium of the gear-wheel D, impart motion to the lantern-wheel 65 g and the shaft C'. Upon the shaft C' is rigidly mounted a spur-wheel, E, which has upon its front face two outwardly-extending pins, i, located diametrically opposite one another. 70

E' represents a shaft, which is mounted in the sides of the casing, just below the shaft C'. Upon said shaft is mounted a pallet, j, which engages the spur or escape wheel E, one tooth at a time. It will thus be seen that an oscillating isochronous movement will be imparted 75 to said shaft and pallet. Extending outwardly from the shaft E' is a rod, k, having a knob or hammer at its end. Said hammer and rod are so located that when the shaft E' is oscillated they will be vibrated and the bell rung. 80

E² represents an arm, which is secured by its lower end to the shaft E', said arm being bent at right angles to its body portion, as shown at l. The bent end of said arm extends through an opening in the front of the casing, and fits an aperture or opening in a shifting lever, G, which lever G is pivoted at its upper end to the front of the casing. The lower of said shifting-lever is bent inwardly 90 and then continued downwardly on a parallel line with the upper end of the said lever, but on a different plane. By shifting said lever one of the teeth of the pallet is held rigidly in engagement with the teeth of the escape-wheel, and prevents the same from turning. 95

H represents a pivoted stop, which consists of a strip of metal substantially L shape in form, having its free end turned inward, said free end being adapted to bear against one of the pins i, located adjacent thereto. A spring, m, is attached to the said stop at one end and

to the door or other object to which the alarm may be attached at its other end, thus holding said stop in place.

I represents a wire, which is attached to the 5 stop at its upper end, the lower end of said wire being connected with chains o, which are attached to the clamp or yoke upon the knob-spindle on opposite sides of the vertical center of the same, so that when said knob-spindle is turned the stop through the connecting means described will be lowered and release the pin i.

The operation is as follows: The spring is wound by turning the shaft a', and the gearing 15 prevented from turning by the pivoted spring-actuated stop H, engaging one of the outwardly-extending pins of the escapement-wheel. When the knob is turned in either direction, the said spring-actuated stop is 20 moved from engagement with said pin, and the gearing is set in motion by the force of the spring, thus imparting movement to the pallet-shaft and pallet, thereby causing the bell to be rung by the hammer connected with said pallet-shaft until the opposite pin of the escapement-wheel comes into engagement with the 25 stop H. This is caused by the knob being released; but should the knob be held in a turned position the alarm will be rung until the force 30 of the actuating-power is expended. For allowing the knob to be turned without ringing the alarm, the end of the shifting lever which works in a vertical slot, n, in the cover p is depressed and moved into a seat, q, of said cover. 35 This movement of the shifting lever causes the same to come in contact with the arm E² on the pallet-shaft, and thereby holds one of the teeth of the pallet in engagement with the escapement-wheel, and prevents the same from being 40 turned. It will thus be seen that when the knob is turned it will have no other effect upon the alarm than to remove the stop H from engagement with the pin of the escapement-wheel; but as said wheel is locked by 45 the pallet it will be seen that as soon as the knob is released said stop will be forced into engagement with said pin by means of the spiral spring. To allow the alarm to ring continuously, when the knob is turned, until 50 the force of the actuating-spring is expended, I provide a wire arm, K, having a shoulder, r, formed by bending said arm, said shoulder

being located just below the upper face of the pivoted stop H, said arm being pivoted at its upper end, its lower end extending downwardly through a slot or opening in the cover, which slot or opening is cut away to form a shoulder, s. When it is desired that the alarm shall ring continuously, the arm is depressed and moved into the recessed portion of the 60 slot, and bears against the shoulder. As soon as the knob is turned, it lowers the pivoted spring-actuated stop, which is engaged by the shoulder on the spring-arm; which holds the said stop from engagement with the pins of 65 the escapement-wheel, thus allowing said wheel to turn until the spring is run down.

It will be seen from the above description that by the use of my improvement the alarm may be so arranged that the door can 70 be opened without operating the same; that the alarm can be so adjusted that it will ring while the escapement-wheel is making one-half of one revolution, or that the bell may be allowed to ring continuously until the force 75 of the spring-actuating power is expended.

The alarm above described is simple in its construction, easily applied, effective in its operation, and can be supplied at a comparatively slight cost.

Having fully described my invention, what I claim as new, and desire to secure by Letters Patent, is—

1. In a burglar-alarm, the combination, with a spring-actuated train of gearing, of a shaft, 85 having an escapement-wheel mounted thereon, a pallet to engage said escapement-wheel, outwardly-extending pins on the escapement-wheel, a pivoted spring-actuated stop, and a pivoted shouldered arm for engaging said stop, 90 substantially as set forth.

2. In a burglar-alarm, the combination, with a spring-actuated train of gearing, of a shaft carrying an escapement-wheel, a shaft carrying a pallet to engage the escapement-wheel, 95 an angular arm projecting from the pallet-shaft, and a shifting lever to engage said angular arm, whereby the alarm may be rendered inoperative, substantially as set forth.

CYRUS P. BACHELDER.
